[57] CLAIM

The ornamental design for a handle, as shown and described.

DESCRIPTION

FIG. 1 is a front elevational view of a handle showing my new design; the rear elevational view appears substantially the same as the front;

FIG. 2 is a bottom plan view thereof;

FIG. 3 is a top plan view thereof; and,

FIG. 4 is a right end elevational view thereof; the left end elevational view appears substantially the same as the right.

FIG. 1

FIG. 2

FIG. 3

FIG. 4
